UNITED STATES PATENT OFFICE.

LORENZO K. JOHNSON, OF PORTLAND, PENNSYLVANIA.

SPRING-CALK DRIVE-SHOE.

1,282,846.

Specification of Letters Patent. Patented Oct. 29, 1918.

Application filed May 12, 1915. Serial No. 27,649.

To all whom it may concern:

Be it known that I, LORENZO K. JOHNSON, a citizen of the United States, residing at Portland, in the county of Northampton 5 and State of Pennsylvania, have invented a new and useful Spring-Calk Drive-Shoe, of which the following is a specification.

The device forming the subject-matter of this application is a horseshoe, and the invention aims to provide novel means for 10 holding a calk in place on the shoe.

The invention aims, specifically, to provide a horseshoe, the calk receiving opening of which is crossed by a bridge which, coacting 15 with the arms upon the calk, expands the said arms into a flared portion of the opening.

It is within the province of the disclosure to improve generally and to enhance the 20 utility of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made 30 within the scope of what is claimed, without departing from the spirit of the invention.

In the accompanying drawing:

Figure 1 shows in bottom plan, a horseshoe constructed in accordance with the present invention;

Fig. 2 is a top plan of a horseshoe constructed in accordance with the present invention;

Fig. 3 shows the shoe in side elevation; 40 Fig. 4 is a cross-section taken approximately on the line 4-4 of Fig. 2, one of the calks being in place; and

Fig. 5 is a section taken approximately on the line 4-4 of Fig. 2, the calk being removed.

In carrying out the present invention there is provided a shoe 1 equipped adjacent its toe with depending bosses 2 and provided adjacent its heels with depending bosses 3. 50 Extended through the bosses 2 and 3, and through the body portion of the shoe, vertically, are openings 4 which flare adjacent their upper ends as indicated at 5. Extended across the openings 4 and located in 55 the flared portions 5 thereof are bridges 6 of blunted wedge-shape and comprising

downwardly extended, approaching walls 7. The calks 8 may be variously constructed, so far as their ground-engaging ends are concerned, it being a matter of common 60 knowledge that the calks will be sharpened or pointed to a greater or less extent depending upon the condition of the roadway to be traversed, the common practice being to use a duller calk in the summer season 65 than in the winter, when the roadway is ice covered. In general, the calks 8 may be shaped as found expedient, so far as their gripping functions are concerned. Each calk 8, however, embodies a tapered stem 9 70 defining a shoulder 10, the stem 9 being bifurcated to form arms 11, and the shoulder 10 abutting against the under face of the shoe when the calk is driven home in the opening 4. The arms 11 coact with the inclined faces 7 of the bridge 6 and are forced laterally, and expanded into the flared portions 5 of the openings 4.

From the foregoing it will be seen that there is presented in this application, a novel 80 means whereby a calk may be securely assembled with a shoe, it being necessary merely to drive the calk to a firm seat, by means of a hammer or like tool, no other implements being necessary. By referring particularly to Figs. 4 and 5 it will be noted that the bridge 6 extends downwardly below the lower end of the flared portion 5 of opening 4. Consequently, as shown in said figures, the lower ends of the passages between the bridge 6 and the walls of the flared portions are of greater width than the free terminals of the arms of the calk. Thus when these arms are first inserted into the opening 4, their free ends will enter 95 readily into the enlarged lower ends of the calk-receiving spaces so that their insertion will not be resisted by the bottom of the bridge 6.

Having thus described the invention, what 100 is claimed is:

The combination with a horseshoe having an opening extending thereinto, the lower portion of the opening having its walls parallel and the upper portion of the opening being flared, and a bridge within the flared portion of the opening and forming diverging passages of greater width at their lower ends than at their upper ends, said bridge being trapezoidal in cross-section and 105 the lower face of the bridge constituting a flat thrust bearing located between the top 110

and bottom faces of the horseshoe, opposed walls of the bridge overhanging the lower ends of said passages to constitute deflecting means, of a calk including a shank 5 adapted to fit snugly within the lower portion of the opening and to abut against the flat thrust bearing of the bridge, and arms extending from the shank, the free ends of the arms being insertible into the en-

larged lower ends of the passages, said 10 bridge constituting a seat for the calk.

In testimony that I claim the foregoing as my own, I have hereto affixed my signature in the presence of two witnesses.

LORENZO K. JOHNSON.
